(74) *Attorney, Agent, or Firm* — Birch, Stewart, Kolasch & Birch, LLP(57) **CLAIM**

The ornamental design for a body of display cabinet as shown and described.

DESCRIPTION

1. Body of display cabinet

1.1 : Top perspective view

1.2 : Front

1.3 : Back

1.4 : Left

1.5 : Top

1.6 : Bottom perspective view

1.7 : Top perspective view 2

1.8 : Front view 2

1.9 : Back view 2

1.10 : Left view 2

1.11 : Top view 2

1.12 : Bottom perspective view 2

1.13 : Top perspective view 3

1.14 : Front view 3

1.15 : Top perspective view 4

(Continued)

- 1.16 : Front view 4
1.17 : Back view 3
1.18 : Left view 3
1.19 : Top view 3
1.20 : Bottom perspective view 3
1.21 : Top perspective view 5

The broken lines depict portions of the body of display cabinet that form no part of the claimed design; reproduction 1.1 is a top perspective view of the body of display cabinet; reproduction 1.2 is a front view thereof; reproduction 1.3 is a back view thereof; reproduction 1.4 is a left view where the right view is a mirror image; reproduction 1.5 is a top view where the bottom view is a mirror image; reproduction 1.6 is a bottom perspective view thereof; reproduction 1.7 is a top perspective view in a condition that the shutter door is partially closed; reproduction 1.8 is a front view of reproduction 1.7; reproduction 1.9 is a back view of reproduction 1.7; reproduction 1.10 is a left view of reproduction 1.7 where the right view is a mirror image; reproduction 1.11 is a top view of reproduction 1.7 where the bottom view is a mirror image; reproduction 1.12 is bottom perspective view of reproduction 1.7; reproductions 1.13 and 1.14 are a top perspective view and a front view showing the state where bags are displayed at both front and back of the same shelf; reproduction 1.15 is a top perspective view in a condition where the shutter door is completely closed; reproduction 1.16 is a front view of reproduction 1.15; reproduction 1.17 is a back view of reproduction 1.15; reproduction 1.18 is a left view of reproduction 1.15 where the right view is a mirror image; reproduction 1.19 is a top view of reproduction 1.15 where the bottom view is a mirror image; reproduction 1.20 is a bottom perspective view of reproduction 1.15; reproduction 1.21 is a top perspective view showing

the use state where bags are displayed with the shutter door closed; this design is for a body of the display cabinet that can display products such as bags; each shelf is separated into two parts, front and back, and an accordion-type shutter door that can be opened and closed is installed between them; so, a user can use the space divided into front and back; this design can store the bags and the like in optimal condition by using the control panel at the front of the drawer; reproductions 1.1 to 1.6 show the state in which the shutter door is open, and reproductions 1.7 to 1.14 show the state in which the shutter door is partially closed, and reproductions 1.15 to 1.21 show the state in which the shutter door is completely closed.
